UNITED STATES PATENT OFFICE.

CHARLES H. HOWARD, OF SAUGUS, MASSACHUSETTS, ASSIGNOR TO PAPER PRODUCTS MACHINE COMPANY, OF BOSTON, MASSACHUSETTS, A CORPORATION OF MASSACHUSETTS.

PAPER-REINFORCING MACHINE.

1,337,702.

Specification of Letters Patent. Patented Apr. 20, 1920.

Application filed August 1, 1916. Serial No. 112,599.

To all whom it may concern:

Be it known that I, CHARLES H. HOWARD, a citizen of the United States, residing at Saugus, Massachusetts, have invented an Improvement in Paper-Reinforcing Machines, of which the following description, in connection with the accompanying drawings, is a specification, like characters on the drawings representing like parts.

10 The invention to be hereinafter described relates to machines for reinforcing fabrics, and more particularly to that type of such machines wherein paper or similar material is strengthened or reinforced by means of transversely extending filaments such as threads, tapes, or other strengthening strips.

Various attempts have been made heretofore to provide a machine to carry out this general purpose, and in some of such attempts there have been provided rotary means for carrying spools of thread and companion rotary means for drawing the required length of thread from the spool carrying rotary means. In others, an individual reciprocating gripper has been employed, but these prior attempts have not met the desired economic production on account of the necessary weight of the rotary means employed together with the load carried and the necessity for interposition of a transferring means between the material to be reinforced and the rotary means. This necessity for transferring the threads from the rotary means to the material to be reinforced has also necessitated complication in the mechanical means employed and has introduced unreliable action in the operation of the mechanisms. Where the prior attempts have used individual reciprocating devices or shuttles for introducing the transverse reinforcing threads, the operation of the machines have been necessarily slow with the result of increased cost in production.

45 With these and other considerations in view, one of the important features of the present invention is to provide means for drawing the threads or other reinforcing filaments successively from a source of supply and conveying them transversely for direct delivery to the material to be reinforced. By this manner of introducing the transversely extending reinforcing filaments the mechanical problems are simplified, rapidity

of production results and reliability in the 55 uniformity of product produced is insured.

Another important feature of the present invention consists in a series of arms which are successively and progressively moved in a direction transversely of the material to be reinforced, to distend the reinforcing filaments successively in a transverse direction and deliver such transversely distended filaments one after the other in succession to and upon the material to be reinforced. 60 65

Various other important features of the invention will be hereinafter described as well as those referred to and then the various novel features of the invention will be definitely pointed out in the claims. 70

In the accompanying drawings is illustrated a good practical form of the invention but it will be understood of course, that the invention is not necessarily restricted to the particulars and details shown, as these 75 may be variously changed within the true scope of the invention and pointed out by the claims.

In the drawings:—

Figure 1 is a plan view of the machine 80 embodying the present invention.

Fig. 2 is an end view of the machine shown in Fig. 1 looking from the right.

Fig. 3 is a cross section taken substantially through the center portion of the machine. 85

Fig. 4 is an enlarged longitudinal sectional view of one end of the machine.

Fig. 5 is a similar longitudinal view through the other end of the machine.

Fig. 6 is a cross sectional view showing 90 the arm actuator and its guiding means.

Fig. 7 is a cross sectional view on the line 7—7 of Fig. 4, some of the parts being broken away to show the construction beyond.

Fig. 8 is a cross sectional view on line 8—8 of Fig. 4.

Fig. 9 is an enlarged detached detail showing more particularly the relation of the compression and calender rolls and the gripping ends of the transversely movable arms, and also, the cutting means for cutting the reinforcing filaments and releasing them from the arms as they are progressively delivered to the material to be reinforced. 100 105

Fig. 10 is a perspective view in detail showing the means for unlocking the gripping jaws.

Fig. 11 is a perspective view in enlarged detail showing the means for closing the gripping jaws upon the reinforcing filaments.

5 Fig. 12 is a sectional detail showing the cutter and its connection with the compression roll.

Fig. 13 is a detailed perspective of one of the gripper jaws showing the plural formation 10 of the gripping elements to enable threads of different dimensions to be clamped by the jaws.

As hereinbefore noted the primary purpose 15 of the present invention is to reinforce a fabric such as paper by means of transversely extending reinforcing filaments delivered directly thereto from a rotary and transversely moving member or element, but it is within the purport of the present invention 20 to also introduce longitudinally extending reinforcing filaments and, if desired, to inclose the reinforcing filaments, whether transversely or longitudinally extending, or both, between two superposed plies or webs of paper or other fabric. Whether a single web of material is to be 25 reinforced or two of such fabrics or webs and to have interposed between them the reinforcing filaments, it is usually desirable 30 to provide one of the surfaces of the fabric to be reinforced with an adhesive to which the transversely extending reinforcing filaments are directly delivered from the rotary drawing means.

35 This adhesive surface may of course, be applied to the paper or fabric as it is being fed to reinforcing position or it may have been previously applied and then made adhesive by dampening as it is fed directly 40 from a source of supply such as a roll or if desired directly from a paper making machine.

Referring to the drawings, there is mounted 45 between the stands 1 rising from suitable base 2 a support 3 for sustaining the main portions of the rotated filament drawing means. In the present instance of the invention the support 3 consists of a tubular member suitably secured to the stands 1, and 50 stationary therewith, but it is obvious that the support for the moving parts to be described may be otherwise contrived.

Extending longitudinally relative to the support 3 and preferably within the same, 55 is a shaft 4 having at one end thereof and fixed thereto a pulley 5 about which extends the belt 6 from a driving pulley 7 secured to a driving shaft 8.

The driving shaft 8 may be actuated from 60 any suitable source of power and as here shown it is turned by means of belt 9 and pulley 10 which is secured to the shaft 8 substantially as shown in Fig. 1.

The shaft 4 provides a convenient means 65 for driving the rotary member or members

by which the reinforcing filaments are drawn from a source of supply in successive order and delivered directly to the surface of the material to be reinforced.

Rotatively mounted upon the support 3 70 preferably at one end thereof is a member for carrying a series of spools or other holders on which is mounted the reinforcing material or filaments. In the present instance of the invention the said member comprises a series of disks 11, which may be secured to a hub 12, mounted to rotate upon the support 3 and sustain between them a series of spools or other holders 13. In order that the number of transversely extending 75 reinforcing filaments per unit of length of material reinforced may be varied within wide limits the spools or holders 13 between the several disks or other like supports rising from the hub 12 may be arranged in staggered relation. While only two series of the spools or holders 13 are illustrated in the present drawings it is to be understood that the number of disks and the number of series of spools or holders 80 which may be sustained by the supply member, may be increased so that the number of transversely extending reinforcing filaments per unit of length on the material to be reinforced may be many or few. 90

In order that the shaft 4 may be properly sustained the supporting member 3 has transversely extending portions 14 carrying bearings 15 through which the shaft 4 extends and by which it is rotatively supported. Secured to the shaft 4 is a gear 16, Fig. 4 which meshes with an internally toothed gear 17 secured to the hub portion 12 of the supply supporting member. Referring more particularly to Fig. 7 the internally toothed 105 gear 17 may be provided with a flanged portion 18 and be secured to the hub portion 12 by suitable means such as the bolts 19, the construction being such that as the shaft 4 is rotated the series of disks carrying the supply spools will be properly rotated in a plane extending at right angles to the axis of the support 3. 110

As hereinbefore noted the reinforcing filaments may be of any appropriate character 115 but as herein indicated, Fig. 4, they consist of threads or like material 20 which lead from their respective supply spools 13 through suitable guides 21 and 22.

By mounting the supply member carrying the spools 13 for rotative movement at right angles to the axis of the support 3 a more effective and mechanically operated action is secured and greater weight may be carried without the introduction of disturbing force as would occur were the supply disks differently arranged. 120

It is the purpose of the present invention that the reinforcing filaments or threads 20 shall be taken from the source of supply and 130

delivered in continuous succession to the surface of the material to be reinforced, and to make the action clear, it is appropriate at this time to describe the means for guiding the material or fabric to and from the reinforcing position.

Mounted in suitable frames 23, Figs. 1 and 3 rising from the supporting foundation are the guiding and delivering rolls for the material to be reinforced. Each of the frames 23 is provided with a guideway 24 for a feed roll 25 which may be appropriately adjusted by means of screw 26 toward and from its companion feed roll 27. Referring to Fig. 2 it will be noted that the axis of the feed roll 25 is mounted in the slide box 28 which by means of the screw 26 may be appropriately adjusted to regulate the pressure between the feed rolls 25 and 27. Mounted on the shaft of the lower feed roll 27 is a gear 29 which may be driven from any suitable source of power as by the gear 30 on the main driving shaft 8 and through the idler 31, the construction being such that when the shaft 8 is turned the feed roll 27 and the companion feed roll 25 will be appropriately turned to feed the material or fabric *a*, between them. If the material or fabric *a*, Fig. 3 has not been previously treated with an adhesive, such adhesive may be supplied to the surface of the material or fabric *a*, as it passes between the rolls 25 and 27 or at any other desired location. In the present instance the frames 23 support between them a tank 32 of any desired character for holding an adhesive liquid which may preferably be of waterproof character. In case the surface of the material has been previously gummed the liquid in the tank 32 may be simply a moistening liquid.

Mounted for rotary movement in the frames 23 are the rolls 34-35, which are similarly supported and guided for adjustment toward and from each other as are the rolls 25 and 27. As indicated in Fig. 2 the roll 34 is mounted in a sliding box 36 which is adjustable by means of screw or other device 37, and the roll 35 is provided with a gear 38 which through idler 39 and the idler 31 may be driven from the gear 30 on the main driving shaft 8, the construction being such that upon rotation of the driving shaft 8 the rolls 25, 27 and the rolls 34, 35 will be rotated to guide and move the material or fabric *a*, to and from the reinforcing position as will presently appear.

It may sometimes be desirable to superpose another web of material or fabric upon the fabric *a* and this is indicated in Fig. 3 where the fabric or web *b*, is taken from a source of supply and passed between the rolls 34, 35.

The reinforcing filaments or threads are to be drawn from supply spools and dis-

tended transversely of the web or material to be reinforced and then delivered by such drawing and distending means directly upon the surface of the material or web to be reinforced. To effect this operation expeditiously and continuously at the desired speed the present invention contemplates that the drawing and distending means shall consist of a series of arms which while movable in a continuous path or rotated about the axis of the support 3 shall be moved successively and progressively in a longitudinal direction transversely of the fabric to successively and continuously deliver filaments one after the other directly to the surface of the web or material to be reinforced.

In carrying these features of the present invention into practical effect there is provided a fixed inclined guide or directing member with which is rotatably associated an actuator for a series of drawing and distending arms. In the present instance of the invention the guide or director consists of a ring 40, Figs. 2 and 4 having a guiding recess therein for the reception of the circular or ring portion 41 of the actuator 42. The guide or director 40 may be secured in substantially inclined position by any appropriate means, but in the present instance of the invention said guide or director is provided with a center-supporting sleeve 43 fitted upon support 3 and secured thereto by a bolt 44, Fig. 4, the construction being such that the director or guide 40 while maintained in inclined position may cause the actuator 42 to travel in a path inclined to the axis of the support 3. In order that the inclination of the guide or director 40 may be changed to suit the width of the fabric being reinforced the sleeve 43 has extending therefrom the hub portions 45, Fig. 6 for the reception of pins 46 secured to the guide or director 40, the construction being such that loosening the clamping bolt 47, the guide or director 40 may have its inclination changed with respect to the axis of the support 3 and then held in such position by tightening the bolt 47. Other means for incline adjustment of the guide or director 40 may suggest themselves to those skilled in the art but that herein described furnishes a good practical form of this feature of the invention.

Rotatably mounted upon the support 3 is an extending hub or sleeve 48 to which is secured by suitable means such as bolt 49, a gear 50 having the internal teeth 51 which are adapted to engage the teeth of gear 52, Figs. 4 and 8 secured to the shaft 4. Rotatably mounted upon the support 3 is the hub 53 carrying the fingers 54, said hub 53 and fingers 54 being secured to the internally toothed gear 50 by suitable means, such as bolts 49, which secure the said gear to the sleeve 48, the construction being such

that as the sleeves 48 and 53 are rotated from the shaft 4, the fingers 54 alternately engage and move the actuator 42 in its inclined circular path. The actuator 42 is 5 preferably formed as indicated in Fig. 6 and provided with two diametrically supported slots 55 adapted to receive the operating fingers 54 as said fingers are rotated in their circular path at right angles to the axis of 10 the support 3. The described means for operating the actuator 42 has been found to be simple and efficient in structure but it will be understood that the means for operating the actuator 42 in its inclined path may be 15 variously changed within the true scope of the present invention. In order to maintain the sleeves 48 and 53 in adjusted position upon the support 3 collars 56 and 57 may be employed substantially as indicated in Fig. 20 4, suitable set-screws 58 serving to hold the collars in adjusted position longitudinally on the support 3.

Secured to the hub 48 and preferably, but 25 not necessarily, cast integral is the guide 59 Fig. 4 having guiding portions 60 provided with slots through which pass the drawing and distending arms 61.

The drawing and distending arms 61 are 30 connected by links 62 with the actuator 42, and as a preferred means to this end, each link 62 is provided with ball and socket joint connection 63 with the actuator 42. The other end of the links 62 are connected 35 with the drawing and distending arm 61 by slot and pin 64 as indicated in Fig. 4 and for a purpose that will presently appear, the construction being such that as the actuator 42 is moved in its inclined path the connected drawing and distending arms which 40 rotate in unison therewith will be reciprocated in the guide member 59.

It is the purpose of the drawing and distending arms to draw the filaments from the source of supply or spools 13 and distend such filaments in transverse relation 45 with the material or web to be reinforced, and to expeditiously effect this purpose, especially where wide material or webs are to be reinforced the illustrated form of the 50 invention shows the drawing and distending means duplicated at each side of the machine although of course, where narrow webs or material are to be reinforced one such drawing and distending means may be 55 sufficient. Where however, the drawing and distending means are duplicated as in the illustrated form of the invention it is necessary to provide that one of said drawing and distending means shall draw the reinforcing 60 filament from the source of supply, carry it part way across the width of material or web and then deliver the end of the reinforcing filament to the drawing and distending means at the opposite side of the 65 machine. Each of the drawing and distend-

ing arms 61 is provided with jaws to grasp and release the reinforcing filaments, and since said jaws, except as to their time of operation, may be substantially the same for all of the drawing and distending arms, a 70 description of one will be sufficient.

Referring to Fig. 9 of the drawing, the drawing and distending arm 61 is provided with a recess at its end portion in which is mounted a jaw member 65 provided with an 75 elongated slot through which extends a pin 66. A spring 67 acting on the jaw member 65 normally forces the jaw member 65 toward the opposite jaw member 68 but yields sufficiently to permit the proper clamping 80 between the jaw members of threads or filaments of different dimensions.

The jaw member 68 is provided with a shank portion 69 normally under the influence of a spring 70 tending to force the 85 jaw member 68 into open relation with jaw member 65. The shank 69 of the jaw member 68 has a locking recess 71 in which is adapted to engage the lock 72 formed as a slide. A spring 73 acting upon the lock 72 90 normally forces the lock 72 into locking engagement with the recess 71 to maintain the jaw member 68 in clamping relation with the jaw member 65. Pivotaly mounted at 74 is a lock controller 75 the end of which 95 is adapted at times to be moved in opposition to the spring 73 to force the lock 72 out of the notch 71 and permit the jaw 68 to move out of clamping relation with the jaw 65. As indicated in Fig. 13 each of the 100 drawing and distending arms is preferably provided with a plurality of yielding jaw members 65, two being shown in Fig. 13, but it is obvious that any appropriate number may be employed, the purpose being that 105 each drawing and distending arm may act upon a plurality of reinforcing elements or threads and carry them into transverse position in relation to the fabric or material to be reinforced.

The present invention in the form illustrated contemplates that the drawing and distending arms at the one side of the machine shall draw one or more threads or filaments from the supply, carry them toward the opposite side of the machine and then deliver the ends of such filaments or threads to the drawing and distending arms at the opposite side of the machine which thereupon complete the transverse drawing 110 and distending movement of the filaments or threads. It therefore becomes necessary for the drawing and distending arms at the supply side of the machine to clamp the threads or filaments in the jaws when said 115 arms are in retracted position, then carry these toward the opposite drawing and distending arms, release the threads or filaments at this point so that the jaws of the drawing and distending arms at the oppo- 120 125 130

site side of the machine may be clamped on the ends of the threads or filaments and complete the transverse movement.

Mounted on the stand 23, Figs. 4 and 11 5 is a jaw closer comprising a cam piece 76 connected to a rod 77 which may be appropriately secured to the framing 23, as by means of the nuts 78 threaded to the stand 77, the construction being such that when 10 the drawing and distending arms successively reach their retracted position as indicated in the lower portion of Fig. 4 and are being carried in their rotary path, the jaw 68, Fig. 11, will ride up the incline of 15 the cam 76 and force the jaws into closed relation upon the reinforcing filaments or threads, the lock 72 thereupon becoming effective to hold the jaw clamped upon the filaments or threads.

20 When the drawing and distending arms at the supply side of the machine meet the drawing and distending arms at the opposite side of the machine, the jaws of the arms on the supply side of the machine will 25 open and the jaws of the arms at the delivery side of the machine are closed upon the projecting ends of the filaments or threads. To effect this purpose as the drawing and distending arms move in their 30 endless or circular path, there is mounted upon the support 3 a stand 79 having secured thereto an opener for the delivery jaws at the supply side of the machine substantially as indicated in Fig. 4. This 35 opener comprises a cam piece 80, supported by a stem 81 adjustably secured in the stand 79 and such cam piece is provided with inclined surface 82, Fig. 10, along which rides the end 75 of the lock controller 40 as the drawing and distending arms move in their endless or circular path. The lock controller 75 will thus be moved to the right, view Fig. 9 of the drawing, withdrawing the lock 72 and permit the jaws 45 carried by the arms on the supply side of the machine to release the filaments or threads 20. The ends of the filaments or threads 20 extend somewhat beyond the jaws and are thereby grasped by the jaws 50 of the arms at the opposite side of the machine when these arms meet. To effect this closing movement of the jaws at the delivery side of the machine there is mounted on the stand 83, Figs. 2 and 4, a closing cam 55 76 similar to that illustrated in Fig. 11, which acts upon the jaw 68 to close it as hereinbefore pointed out. Thereupon the arms at the supply and delivery side of the machine return to their outward position, 60 the filaments or threads slipping through the jaws of the arms at the supply side of the machine as the jaws at the opposite side of the machine distend the threads fully into their transverse relation with the fabric or material to be reinforced.

The threads are now in position transversely of the fabric or material and are to be delivered thereto as indicated in Fig. 9, the jaws at the supply side of the machine, at this time, that is when the arms have 70 been fully retracted, being again closed upon the filaments or threads as hereinbefore described.

An important feature of the present invention as hereinbefore noted is the direct 75 delivery of the reinforcing filaments to the fabric or material to be reinforced from the drawing and distending means, as such means successively draw and distend the threads and move in their continuous or 80 circular path. The threads should not be released from the jaws of the drawing and distending arms until after they have been placed upon the material to be reinforced and secured thereto. There must therefore 85 be a period of dwell of the drawing and distending arms during a portion of their continuous or circular path movement in order that they may hold the threads and deliver them to the material and release 90 them only after the material has taken charge of them. It will now be apparent why the drawing and distending arms are connected to their operating links 62 by the yielding connection 64, said yielding 95 connection permitting movement of the actuator 42 to a limited extent of its travel without giving longitudinal movement to the drawing and distending arms, the effect being that the filaments or threads 100 may be delivered directly to the material to be reinforced while still held by the drawing and distending means.

To insure the dwell in the longitudinal movement in the drawing and distending 105 means at the time the filaments are to be delivered to the material, each of the arms 61 is provided with a shoulder 84, Figs. 4, 5 and 9 which shoulders are adapted to engage the wall 85 of the guides 60 and prevent further longitudinal operating movement of the drawing and distending arms while the actuator 42 moves the links 62 against the tension of the spring 86. The length of the slot and pin connection between the links 64 and the drawing and distending arms is sufficient to permit the desired dwell in the longitudinal movement of the drawing and distending arms as they and the actuator move in their continuous 110 path about the axis of the support 3.

During this dwell of the drawing and distending arms it is desirable that the filaments or threads be forced into holding engagement with the adhesive surface of the 125 material to be reinforced and to effect this purpose there is mounted opposite the roller 35, Figs. 3 and 4, a compression roller 87. This compression roller 87 may be supported yieldingly to press toward the roller 35 130.

by any suitable means, but in the present form of the invention said compression roller is carried by the arms 88 mounted in supports 89 sustained from the tubular member or support 3, Fig. 4 and normally under the action of a spring 90, Figs. 4 and 5, the construction being such that while the compression roller 87 may force the threads 5 yieldingly upon the surface of the fabric 10 passing about the roller 35 it may yield to permit different thicknesses of threads to pass. This action of the compression roller 87 takes place while the drawing and distending arms 61 dwell in their longitudinal 15 movement already described and are moved in their continuous path about the support 3. The filaments or threads having now been placed upon the material to be reinforced they are released from the drawing and distending arms to permit them to pass along 20 with the reinforcing material. This release at the delivery or right-hand side of the machine indicated in Fig. 9 is effected by an opening movement of the jaws caused by 25 the cam 80 acting on the locking controller 75. The release of the filaments or threads from the drawing and distending arms at the supply side of the machine is effected by a cutter which cuts the filaments or 30 threads a short distance beyond the jaw or said arms after said jaws have been clamped upon the filaments or threads.

The cutter mechanism may be variously contrived to effect the purpose but a good form thereof is indicated in Figs. 9 and 12 35 wherein the compression roller 87 is provided with recess 91, Fig. 9, into which projects a pin 92 adapted to engage a pin 93 projecting from a cutter disk 94. The cutter disk 94 has a cutting edge 95 and is rotatably mounted in a carrier 96. Said carrier 96 has an opening 97 centrally thereof which embraces a bearing portion 98 of the support 88 for the compression roll 87. The opening 97 is elongated as indicated in Fig. 40 to permit the cutter carrier 96 to move toward and from the roller 35. To effect this movement and cause the edge of the circular cutter to cut the filaments or threads 45 as they pass between the compression roller 87 and the roller 35 the said cutter carrier is provided with a projecting arm 99, Fig. 9 upon which is seated one end of spring 100, the other end of spring finding a seat against 50 collar 101 on the support 88, the construction being such that the cutter carrier 96 and 55 force the cutter 94 will be yieldingly pressed toward the roller 35 and serve to cut the filaments between the jaws of the 60 drawing and distending arms at the supply side of the machine and the edge of the fabric being reinforced, quite regardless of whether such fabric and threads are more or less thick or thin.

65 It may be desired at times to introduce

longitudinally extending reinforcing filaments in addition to the transversely extending filaments and in such case there is mounted in the stands 23 a guide roll 102 about which these longitudinal threads may 70 be guided to and about the compression roller 87, said longitudinal threads or filaments preferably being introduced at the bite between the rolls 87 and 35.

From the construction described as one 75 good practical form of the invention it will be apparent to those skilled in the art that the present invention provides a machine for reinforcing fabrics or materials such as paper or the like by introducing trans- 80 verse reinforcing filaments directly to the material to be reinforced from the drawing and distending means; and it will be further noted that the present invention provides drawing and distending means which continuously and progressively draw from a source of supply the reinforcing filaments, 85 progressively distend them transversely of the material to be reinforced and delivers such transversely distended filaments successively to the material to be reinforced. 90

What is claimed is:—

1. In a machine of the character described, the combination of means for guiding material to be reinforced by transversely 95 extending filaments, drawing and distending arms, means comprising two series of cams for moving said arms in a direction transversely of their length, and means for moving said drawing and distending arms 100 longitudinally as they are moved transversely to draw and distend a series of threads in succession for application to the material to be reinforced.

2. In a machine of the character de- 105 scribed, the combination of means for guiding material to be reinforced by transversely extending filaments and combined rotary and longitudinally moving opposed groups of members relatively movable for drawing 110 and distending the reinforcing elements transversely of the material and delivering said filaments to the material to be reinforced.

3. In a machine of the character de- 115 scribed, the combination of means for guiding material to be reinforced by transversely extending filaments, two series of drawing and distending members, means for moving them longitudinally toward and 120 from each other for drawing and distending a series of filaments in transverse relation to the material to be reinforced, and means for moving them transversely to deliver the filaments to the material to be reinforced. 125

4. In a machine of the character de- 130 scribed, the combination of a rotary support for carrying a supply of reinforcing filaments, a series of longitudinally mov- able drawing and distending arms for draw-

- ing reinforcing filaments from the supply, and means for moving the drawing and distending arms transversely for delivering the distended filaments to the material to be reinforced.
5. In a machine of the character described, the combination of a rotary support for carrying a supply of reinforcing filaments, a series of longitudinally movable drawing and distending arms for drawing reinforcing filaments from the supply, and means for moving the drawing and distending arms transversely for delivering the distended filaments directly to the material to be reinforced and means for introducing longitudinally extending filaments to said material.
10. In a machine of the character described, the combination of guiding means for material to be reinforced, drawing and distending means movable in two directions to draw and distend filaments transversely relative to the material to be reinforced, and transport the filaments toward the material to be reinforced and means for interrupting the movement of the drawing and distending means in one direction that said drawing and distending means may deliver the reinforcing filaments to the material to be reinforced.
15. In a machine of the character described, the combination of guiding means for material to be reinforced, drawing and distending means movable in planes substantially parallel to the axis of the rotary member for drawing and distending filaments transversely of the material to be reinforced, and means for causing the drawing and distending arms to deliver the transversely distended threads to the material to be reinforced.
20. In a machine of the character described, the combination of means carrying a plurality of reinforcing filaments, a series of drawing and distending arms, an actuator for moving said arms longitudinally to draw filaments from the supply means and distend them transversely relative to the material to be reinforced, means for moving the drawing and distending arms transversely in an endless path, and means for suspending the drawing and distending movement of the arms as they move transversely to deliver the reinforcing filaments.
25. In a machine of the character described, the combination of rotary means carrying a series of holders for reinforcing filaments, drawing and distending members, means for moving said members toward and from each other for drawing filaments from the said holders and distending them transversely relative to the material to be reinforced, and means for bodily moving the drawing and distending means transversely in a plane substantially parallel to the vertical plane passing longitudinally through the material to be reinforced.
30. In a machine of the character described, the combination of means for guiding material to be reinforced, a rotatable member carrying a plurality of reinforcing filaments, drawing and distending members arranged in pairs, means for moving the members in each pair toward and from each other for drawing filaments from the rotatable member and distending them transversely of the material, and means for freeing the filaments from the drawing and distending means.
35. In a machine of the character described, the combination of means for guiding material to be reinforced, a rotatable member, a plurality of rows of reinforcing filament holders carried by said rotatable member the holders in one row being staggered with reference to the holders in another row, drawing and distending means acting independently of said rotatable member for drawing filaments therefrom and distending them in transverse relation to the material to be reinforced, and an actuator for the said drawing and distending means.
40. In a machine of the character described, means for directing material to be reinforced, a rotary member, a series of drawing and distending arms movable in planes substantially parallel to the axis of the rotary member for drawing and distending filaments transversely of the material to be reinforced, and means for causing the drawing and distending arms to deliver the transversely distended threads to the material to be reinforced.
45. In a machine of the character described, the combination of means carrying a plurality of reinforcing filaments, a series of drawing and distending arms, an actuator for moving said arms longitudinally to draw filaments from the supply means and distend them transversely relative to the material to be reinforced, means for moving the drawing and distending arms transversely in an endless path, and means for suspending the drawing and distending movement of the arms as they move transversely to deliver the reinforcing filaments.
50. In a machine of the character described, the combination of means for supplying a plurality of reinforcing filaments, a series of drawing and distending arms each carrying a jaw for clamping a reinforcing filament, means for moving said arms successively in a longitudinal direction, means for moving them bodily in a transverse direction, and means for interrupting the longitudinal movement of the arms to permit the delivery of the filaments directly to the material to be reinforced.
55. A machine for reinforcing material by transversely extending filaments, comprising, in combination, means for guiding the material to be reinforced, a supply for a plurality of reinforcing filaments, a series of drawing and distending arms, means for moving said series of arms in a continuous path transversely of their length, means for successively moving said arms longitudinally for successively drawing filaments.

from the source of supply and distending them transversely of the material to be reinforced, and means for freeing the transverse filaments from the drawing and distending arms to permit them to move independently of said arms.

15. A machine for reinforcing material by transversely extending filaments, comprising, in combination, means for guiding the material to be reinforced, a supply for a plurality of reinforcing filaments, a series of drawing and distending arms, each provided with jaw members for clamping filaments of differing dimensions, means for moving said series of arms in a continuous path transversely of their length, means for successively moving said arms longitudinally for successively drawing filaments from the source of supply and distending them transversely of the material to be reinforced, and means for freeing the transverse filaments from the drawing and distending arms to permit them to move independently of said arms.

25. 16. A machine of the character described, comprising, in combination, means for guiding material to be reinforced, devices to press reinforcing filaments onto the material to be reinforced, longitudinally movable drawing and distending means for drawing filaments from a source of supply and distending them in transverse relation to said material, means for continuously moving the drawing and distending means transversely in an endless path, and means for suspending the drawing action of the drawing and distending means to enable the filaments to be delivered to the material.

17. In a machine of the character described, the combination of means for guiding material to be reinforced, rotatable means for supporting a plurality of holders for reinforcing filaments, a series of drawing arms movable longitudinally for drawing filaments from said rotatable means, means for moving the series of drawing arms in a plane parallel to the plane of rotation of the said rotatable means, an actuator, and means for moving the actuator in a plane inclined to the plane of movement of the rotatable means and series of drawing arms.

18. In a machine of the character described, the combination of means for guiding material to be reinforced, rotatable means for supporting a plurality of holders for reinforcing filaments, a series of drawing arms movable longitudinally for drawing filaments from said rotatable means, means for moving the series of drawing arms in a plane parallel to the plane of rotation of the said rotatable means, an actuator, and means for moving the actuator in a plane inclined to the plane of movement of the rotatable means and series of draw-

ing arms and separate connections between the arms and actuator for moving the arms longitudinally.

19. In a machine of the character described, the combination of means for supporting and guiding material to be reinforced, rotatable means for supporting a plurality of holders for reinforcing filaments, opposed series of drawing devices for drawing filaments from the rotatable means, and placing them transversely of the material, said means and devices being rotatable bodily in parallel paths, and means for reciprocating the opposed series of drawing devices transversely of the material.

20. In a machine of the character described, the combination of guiding means for material to be reinforced, a rotary member carrying a plurality of reinforcing filaments, rotary drawing and distending means at each side of the machine for drawing filaments from the rotary member and means for moving the drawing and distending means toward and from each other to place the filaments in transverse relation to the material.

21. In a machine of the character described, the combination of rotatable means for holding a series of reinforcing filaments, a series of drawing devices at each side of the machine, means for moving the series of drawing devices in an endless path substantially parallel to the plane of rotation of the said holding means, means, for moving the drawing devices at each side of the machine toward and from each other and means for transferring filaments drawn from the holding means by one set of drawing means to the control of the drawing means at the other side of the machine.

22. In a machine of the character described, the combination of rotatable means for holding a plurality of reinforcing filaments, a series of arms at opposite sides of the machine movable bodily in a path substantially parallel to the plane of rotation of the holding means, and means for successively moving the arms at opposite sides of the machine toward and from each other to draw and distend filaments transversely of the material to be reinforced.

23. In a machine of the character described, the combination of rotatable means for holding a plurality of reinforcing filaments, a series of arms at opposite sides of the machine movable bodily in a path substantially parallel to the plane of rotation of the holding means, each of said arms being provided with jaws for clamping the reinforcing filaments and means for successively moving the arms at opposite sides of the machine toward and from each other to draw and distend filaments transversely of the material to be reinforced.

24. In a machine for reinforcing paper

material, the combination of means for continuously feeding the material to be reinforced in a longitudinal direction, drawing or distending members mounted for bodily movement in a curved path, and means for moving said drawing or distending members progressively toward and from each other in a direction substantially at right angles to the bodily movement of said members for drawing or distending reinforcing filaments into transverse relation with the material to be reinforced.

25. In a machine for reinforcing paper material, the combination of means for continuously feeding the material to be reinforced in a longitudinal direction, pairs of drawing or distending members mounted for bodily movement in a curved path, means for moving the members of the pairs progressively toward and from each other in a direction substantially at right angles to the bodily movement of said members for drawing or distending reinforcing filaments

into transverse relation with the material to 25 be reinforced, and means for transferring the reinforcing filaments from said members to the material to be reinforced.

26. In a machine for reinforcing paper material, the combination of means for continuously feeding the material to be reinforced in a longitudinal direction, opposed sets of drawing or distending members mounted for bodily movement in a curved path, means for moving the drawing or distending members of said opposed sets progressively in a direction substantially at right angles to the bodily movement of said members for drawing or distending reinforcing filaments into transverse relation 30 35 40 with the material to be reinforced, and means for pressing the distended reinforcing filaments into contact with the material to be reinforced.

In testimony whereof, I have signed my 45 name to this specification.

CHARLES H. HOWARD.
